DETACHABLE HANDLE FOR DRINKING CUPS OR THE LIKE

Kenneth W. Scherrer and Roy A. Scherrer, both of 321 Rother Ave., Buffalo, N.Y.

Filed Oct. 9, 1962, Ser. No. 72,047

Term of patent 3½ years

(Cl. D44—29)

FIG. 1 is a left, rear perspective view of a detachable handle for drinking cups or the like embodying our new design, the cup shown associated therewith in broken lines for illustrative purposes only;

FIG. 2 is a right, front perspective view thereof;
FIG. 3 is a side elevational view thereof, the opposite side view being substantially the same;

FIG. 4 is a top plan view thereof;
FIG. 5 is a bottom plan view thereof;
FIG. 6 is a front elevational view thereof;
FIG. 7 is a rear elevational view thereof.

We claim:

The ornamental design for a detachable handle for drinking cups or the like, substantially as shown and described.
